Inventor:

Thomas S. Minniss

UNITED STATES PATENT OFFICE.

THOMAS S. MINNISS, OF MEADVILLE, PENNSYLVANIA.

COMBINED HEAD-REST AND CANE.

SPECIFICATION forming part of Letters Patent No. 432,759, dated July 22, 1890.

Application filed February 10, 1890. Serial No. 339,911. (No model.)

To all whom it may concern:-

Be it known that I, THOMAS S. MINNISS, a citizen of the United States, residing at Meadville, in the county of Crawford and State of Pennsylvania, have invented a new and useful Improvement to my Combined Head-Rest and Cane, for which a patent was allowed me December 4, 1889, Serial No. 311,745.

The object of my invention is to furnish a cane that can be unfolded with a hand-piece hinged at its outer end, so that when expanded and each half-cane resting on the front of the shoulders the hinged hand-piece will make a rest for the head, while the half-canés on each side are held by the hands, arms, or a strap around the body; and when standing to use the expanded cane as a rest to lean back upon to the relief of tired back and legs.

Figure 1 shows the rest ready for use as such. Fig. 2 is the same folded as a cane. Fig. 3 shows the lock of the parts when closed. Fig. 4 shows the adjustability of the half-canés to the shoulders, as well as the removable cushion, and Fig. 5 is a detached view 25 of the removable cushion.

Similar letters refer to similar parts throughout the several views.

E (shown in dotted lines) is the pivot or hinge on which the hand-piece B swings round 30 on the top of A.

H H is a long straight wire with three hooks I I soldered to one side. Said wire is guttered deep enough to allow the pins K K to pass over and hold it in place. (See K K K, Fig. 35 1.) The loops or staples J J on the other side are made to catch under all the hooks at the same time and hold or wedge them together. The groove is made enough longer than the wire H (see space L, Fig. 3) so that H can slip 40 up and down that distance. When the parts are together and H at its highest point, a tap on the bottom of the cane will shoot all these

wedging-hooks under their several staples, and the lock is complete, and if it is to be opened a tap on the top of the cane will jar H upward when all the hooks let loose at once.

The dotted lines in Fig. 4 show how the flat sides of A A adjust themselves to the shoulders by means of E E. Fig. 4 shows 50 also a removable cushion F, as well as the lock, which the hinged ends of B B make to prevent bending farther backward.

G G are staples, bent in the manner shown, with cloth or leather attached, so that stretched, 55 as in Fig. 4, it gives a softer rest for the head, when desired, than the wood of B B. The shanks M M fit into holes in the backs of B B, as shown by the dotted lines in Fig. 4. Being but about two inches wide by three or 60 four long, it can be carried in the vest-pocket and used or not, as the wearer may desire, for the flattened sides of B B are no harder than the slots of a high-backed chair.

I ferrule both parts of A at top and bottom—at top to strengthen the wood round the screw that makes the pivot E, and at bottom to take the wear as in other canes, for when locked it needs no other.

What I claim as my invention, and desire 70 to secure by Letters Patent, is—

In a combined cane and head-rest, the combination of two half-canés A A, each pivoted to one of two hinged-together hand-pieces B B by the pivots E E, the staples J J, fixed 75 to one of the halves of cane A A, and the hooks I I, attached to the other half of cane and adapted to be locked and unlocked with reference to said staples of the other half, substantially as described.

THOMAS S. MINNISS.
